LOUIS C. HILLER AND FRANKLIN IRVING CAMP, OF MERIDEN, CONNECTICUT.

GAS-BURNER.

1,077,713.

Specification of Letters Patent.

Patented Nov. 4, 1913.

Application filed April 5, 1913. Serial No. 759,106.

To all whom it may concern:

Be it known that we, LOUIS C. HILLER and FRANKLIN IRVING CAMP, citizens of the United States, residing at Meriden, county 5 of New Haven, State of Connecticut, have invented an Improvement in Gas-Burners, of which the following is a specification.

The invention relates to gas burners of the type having a pilot light from which 10 the gas is automatically ignited when turned on, and particularly to gas burners having means whereby the gas may be turned alternately off and on by similar successive movements of a single chain or other operating 15 device.

One object of the invention is to provide a construction in which a relatively small movement of the valve or cock will effectively control the flow of gas in the desired 20 manner.

Other objects of the invention are to simplify and generally improve devices of this character and to provide a self-lighting gas burner which will be convenient and 25 efficient in use and otherwise well qualified to fulfil the requirements of such a device, all as will hereinafter more fully appear.

With these and other objects in view we have devised the novel gas burner which we 30 will now describe, reference being had to the accompanying drawings forming a part of this specification, and in which:

Figure 1 is an elevation, partly broken away, of a gas burner constructed in accordance with the invention; Fig. 2 is an elevation at right angles to Fig. 1 with the inclosing shell removed; Fig. 3 is a section on the line 3—3, Fig. 2; Fig. 4 is a section on the line 4—4, Fig. 3; Fig. 5 is 40 an elevation of the valve operating mechanism, as viewed from the left in Figs. 2 and 4, with certain parts omitted; Fig. 6 is a detail perspective view of the operating member detached.

12 denotes a body having a central longitudinal gas passage 13 and provided at its upper end with a threaded nipple 14 for the attachment of the burner proper (not shown) and at its lower end with a similar 50 threaded nipple 15 for connection with the gas supply pipe, as by means of a union or threaded sleeve coupling 16.

17 denotes an inclosing shell or casing suitably held in place on the body 12, as by

having a portion clamped between the union 55 16 and a shoulder 18 on said body.

19 denotes a passage in the body 12 leading from the main gas passage 13 below or in advance of the controlling valve or cock, hereinafter described, and communicating 60 with the pilot tube.

20 denotes a screw constituting a valve for controlling the passage of gas to the pilot tube. Said pilot tube comprises a section 21, permanently secured within a bore 44 65 in the body 12, and a detachable section or pilot tube proper 22, said sections being connected by a sleeve 23 permanently secured to the section 22 and fitting the end of the section 21.

24 denotes the main gas controlling valve or cock, said valve comprising a tapered plug held in a transverse tapered bore in the body 12 by a screw 25 and washer 26. The valve or plug 24 is arranged with its 75 axis transverse to the axis of the gas passage 13 and at one side thereof, and is provided with a number (preferably greater than two and herein shown as three) of communicating, radially arranged ports 27, as 80 shown most clearly in Fig. 3, said ports forming equal angles with one another. The location of the axis of the valve 24 and the arrangement of the ports 27 is such that two of these ports will register simultaneously with the upper and lower portions of the gas passage 13, respectively. As shown 85 in Fig. 3 the valve 24 is in a position to permit gas to flow through the passage 13 to the burner. If the valve be turned through 90 one sixth of a complete rotation the ports 27 will be moved out of register with the passage 13 and the gas will be turned off. By turning the valve through a further one sixth of a rotation communication between 95 the ports 27 and gas passage 13 will again be established and the gas will be turned on. It will be seen that the location of the valve 24 and the arrangement of its ports is such that only one sixth of a complete rotation of 100 said valve is necessary in order to turn the gas on or off, and that by increasing the number of ports the necessary movement of the valve at each operation may be correspondingly decreased. It will also be observed that by reason of the passage 19 in 105 advance of the valve 24, the flow of gas to the pilot tube, controlled by the screw or

valve 20, is continuous irrespective of the position of the valve 24.

28 denotes a ratchet wheel secured upon the reduced end portion 29 of the valve 24 5 so as to turn therewith. The ratchet wheel 24 is formed with a series of peripheral teeth equal in number to twice the number of the ports 27 and herein shown as six.

30 denotes an operating member the form 10 of which is most clearly shown in Fig. 6. Said operating member is provided with an elongated opening 31 which receives the portion 29 of the valve 24 upon which said operating member is mounted to turn and 15 have a limited sliding movement, said portion 29 serving as a support for said member. The operating member 30 is further provided with an outwardly extending operating arm 32, a laterally extending stop 20 arm 33 arranged to engage the side of the body 12 to limit the turning movement of 25 said member, and a laterally extending pawl arm 34 which engages and coöperates with the teeth on the ratchet wheel 28 to turn said wheel.

35 denotes a spring plate secured to the body 12 by the screw 20 which serves as a valve to control the flow of gas to the pilot tube. The plate 35 has an attaching arm 36, 30 provided with an opening through which the section 21 of the pilot tube projects, and a spring arm 37 coöperating with the teeth on the ratchet wheel 28 to prevent retrograde movement of said wheel.

38 denotes disks secured to the end of the portion 29 of the valve 24 by means of a screw 39 and separated by a washer 40, said disks and washer collectively composing a member having a peripheral groove in 40 which is located a torsion spring 41 one end of which is attached to the arm 36 of the spring plate 35 and the other end of which engages the stop arm 33 of the operating member 30.

42 (Fig. 1) denotes a pull chain secured to the end of the operating arm 32 of the operating member 30. 43 denotes a chain guide secured to the shell 17 and through which the chain 42 passes. The axis of the 50 valve 24, and consequently of the ratchet wheel 28 and operating member 30, is arranged approximately diametrically of the shell 17, or on a chord lying closely adjacent the diameter of said shell, the operating 55 member being located near the end of said chord, and the chain guide 43 is arranged approximately tangential to said shell, or substantially perpendicular to said chord at a point opposite said operating member. It 60 will therefore be seen that the chain 42 exerts a straight and direct pull upon the operating arm 32 without the necessity of making any turns whatsoever within the shell.

65 The operation is as follows: With the

parts in the positions shown in the drawings the gas is turned on. A pull upon the chain 42 causes the operating member 30 to turn upon its axis in a counter-clockwise direction as shown in Figs. 1 and 5 and, by engagement of the pawl arm 34 with one of the teeth of the ratchet wheel 28, to turn said ratchet wheel until the stop arm 33 is brought down into engagement with the wall of the body 12. The arrangement is 70 such that this causes the ratchet wheel, and consequently the valve 24, to make one sixth of a rotation, thereby shutting off the gas by carrying the ports 27 out of register with the gas passage 13. The gas however continues to pass to the pilot tube through the passage 19, thereby maintaining the pilot flame. Release of the chain 42 permits the spring 41 to turn the operating member 30 in a clockwise direction until the stop 75 arm 33 again engages the body 12, thereby returning said operating member to its original position. During this movement the valve 24 is held against retrograde movement by engagement of the spring arm 37 80 with one of the teeth of the ratchet wheel 28, and the elongated opening 31 in the operating member permits said member to slide longitudinally downward to a sufficient extent to cause the pawl arm 34 thereof to ride 85 idly over the adjacent tooth of the ratchet wheel. It will be observed that the engagement of the spring 41 with the arm 33 is such as to cause said spring normally to 90 maintain the operating member in its normal position shown in Figs. 1 and 5, both 100 by turning the same in a clockwise direction and by sliding the same upwardly, when permitted by the engagement of the pawl arm 34 with one tooth, to bring said pawl 105 arm into operative engagement with another tooth. A second pull upon the chain 42 will, in the same manner, cause the valve 24 to be further turned through one sixth of a rotation, thereby again turning on the gas, as 110 above explained, the gas being ignited at the burner by the pilot flame.

Having thus described our invention, we claim:

1. In a gas burner, in combination, a body 115 having a gas passage, a shell inclosing said body, a rotary valve controlling said passage, the axis of said valve being parallel to a diameter of said shell, operating mechanism including an operating arm on the end 120 of said valve within the shell, a guide on said shell arranged perpendicular to said axis at a point opposite said arm, and a chain secured to said arm and passing through said guide.

2. In a gas burner, the combination with a body having a gas passage, of a rotary valve arranged with its axis transverse to the axis of said passage and at one side 125 thereof, said valve having three equally 130

- spaced communicating radial ports of the same size as the gas passage arranged so that two of said ports are adapted to register simultaneously with the passage and allow 5 an uninterrupted flow of gas therethrough.
3. In a gas burner the combination with a body having a gas passage, a valve controlling said passage, a ratchet wheel for operating said valve, and a pilot tube communicating with said passage, of a spring coöperating 10 with said ratchet wheel, and a screw for securing said spring to said body and for controlling communication between said pilot tube and passage.
- 15 4. In a gas burner the combination with a body having a gas passage, a valve controlling said passage, a ratchet wheel for operating said valve, and a pilot tube communicating with said passage, of a spring plate secured 20 to said body, said plate having an attaching arm provided with an opening for said pilot tube and a spring arm coöperating with said ratchet wheel.
5. In a gas burner the combination with a body having a gas passage, a valve controlling 25 said passage, a ratchet wheel for operating said valve, and a pilot tube communicating with said passage, of a spring plate secured to said body, said plate having an attaching arm provided with an opening for 30 said pilot tube and a spring arm coöperating with said ratchet wheel, an operating member for said ratchet wheel, and a second spring secured to said attaching arm for controlling 35 said operating member.
6. A gas burner comprising a body having a gas passage, a rotary valve controlling said passage, a ratchet wheel secured to said valve and having peripheral teeth, and an operating member adjacent said ratchet 40 wheel and having a laterally extending arm coöperating with said teeth, said operating member having an elongated opening to receive the end of said valve whereby said member is mounted on said valve.
7. In a gas burner, a valve operating mechanism comprising a ratchet wheel, a support, an operating member having an elongated opening adapted to oscillate about 45 said support and allow of a sliding movement of the member in addition to the oscillation, an operating arm, a stop arm, and a pawl coöperating with said ratchet wheel.
8. In a gas burner, a rotary valve and operating mechanism therefor comprising an operating member adapted to oscillate and have a limited sliding movement, and means on said member to limit the stroke thereof.
9. In a gas burner, in combination, a body 60 having a gas passage, a rotary valve arranged with its axis transverse to the axis of said passage and at one side thereof, said valve having a plurality of communicating, radially arranged ports coöperating with 65 said passage, and operating mechanism for successively turning said valve through a fraction of a rotation, said mechanism including an oscillating operating member having also a sliding movement and means to limit the stroke of said member.
10. In a gas burner, in combination, a body having a gas passage, a rotary valve controlling said passage, and operating mechanism for said valve including an oscillating operating member having also a sliding movement and provided with a laterally extending arm to engage said body and limit the stroke of said member.
11. A gas burner comprising a body having a gas passage, a rotary valve controlling said passage, a ratchet wheel secured to said valve and having peripheral teeth, and an operating member adjacent said ratchet wheel and having a laterally extending arm coöperating with said teeth, an elongated opening to receive the end of said valve, and a laterally extending stop arm to engage said body and limit the stroke of said member.
12. In a gas burner, in combination, a body having a gas passage, a rotary valve controlling said passage, and operating mechanism for said valve including an oscillating operating member having also a sliding movement and provided with a laterally extending stop arm to engage said body and limit the stroke of said member.
13. A gas burner comprising a body having a gas passage, a rotary valve for controlling said passage, and mechanism for operating said valve including an operating member loosely mounted to oscillate on said valve and slide thereover, a member secured to the end of said valve and having a peripheral groove, and a spring in said groove and engaging said operating member to return the same to normal position after an operation thereof.
14. In a gas burner, the combination with a body having a gas passage and a rotary valve controlling said passage, of operating mechanism for said valve including an oscillating operating member loosely mounted on said valve and having a laterally extending stop arm to engage said body and limit the stroke of said member, a member secured to the end of said valve and having a peripheral groove, and a spring in said groove and engaging said stop arm to return said operating member to normal position after an operation thereof.
15. A gas burner comprising a body having a gas passage, a rotary valve for controlling said passage, and mechanism for operating said valve including an operating member loosely mounted on said valve, a pair of disks secured to the end of said valve, a washer interposed between said disks, and a spring surrounding said washer between

said disks and engaging said operating member to return the same to normal position after an operation thereof.

16. A gas burner comprising a body having a gas passage, a valve controlling said passage, a ratchet wheel for operating said valve, a pilot tube mounted in said bore and communicating with said passage, a spring coöperating with said ratchet wheel and engaging the pilot tube, and a screw for securing said spring to said body, said screw controlling communication between said pilot tube and passage.

17. In a gas burner, the combination with a body having a gas passage and a valve for controlling said passage, of operating mechanism for said valve including an operating member mounted to turn and slide upon said valve, and a spring for returning said operating member to normal position after an operation thereof, said spring being arranged both to turn and to slide said member on said valve.

18. A gas burner comprising a body having a gas passage, a rotary valve controlling said passage, a ratchet wheel secured to said valve and having peripheral teeth, an operating member adjacent said ratchet wheel and having a laterally extending arm co-operating with said teeth, said operating member having an elongated opening to receive the end of said valve whereby said member is mounted to turn and slide upon said valve, and a spring for returning said operating member to normal position after an operation thereof, said spring being ar-

ranged both to turn and to slide said member on said valve.

19. A gas burner comprising a body having a gas passage, a rotary valve for controlling said passage, and mechanism for operating said valve including an operating member mounted to turn and slide upon said valve, a member secured to the end of said valve and having a peripheral groove, and a spring in said groove and engaging said operating member to return the same to normal position after an operation thereof, said spring being arranged both to turn and to slide said member on said valve.

20. A gas burner comprising a body having a gas passage, a rotary valve for controlling said passage, a ratchet wheel for operating said valve, a spring coöperating with said ratchet wheel, an operating member for said ratchet wheel mounted to turn and slide upon said valve and having a stop arm to engage said body and limit the stroke of said member, a member secured to the end of said valve and having a peripheral groove, and a spring in said groove and engaging said stop arm to return said operating member to normal position after an operation thereof.

In testimony whereof we affix our signatures in presence of two witnesses.
